UNITED STATES PATENT OFFICE.

LEWIS P. BRANDEL, OF TAFT, CALIFORNIA.

CORE BARREL.

Application filed August 5, 1924. Serial No. 730,274.

To all whom it may concern:

Be it known that I, LEWIS P. BRANDEL, a citizen of the United States, residing at Taft, in the county of Kern and State of California, have invented new and useful Improvements in Core Barrels, of which the following is a specification.

This invention relates to drilling means, the general object of the invention being to provide means for securing a core of earth by a drill without the same being disturbed by the water used in the drilling operation.

Another object of the invention is to provide means for causing the core barrel to be rotated from the outer barrel.

A further object of the invention is to provide cutting means on both the core barrel and on the outer barrel and to provide means on the outer barrel for reaming the hole to be cut.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a section on line 1—1 of Figure 2.

Figure 2 is an end view of Figure 1.

Figure 3 is a section on line 3—3 of Figure 1.

Figure 4 is a section on line 4—4 of Figure 1.

In these views, 1 indicates a bushing or sub which is threaded to the upper end of the driving barrel 2 and has its upper end threaded to receive the drilling tool. This bushing is provided with a bore through which the water used in the drilling operation passes into the barrel 2. A bushing 3 is threaded at its upper end to receive the lower end of the barrel 2 and its lower end is threaded exteriorly to engage the threaded socket of a shoe 4 which is formed with the teeth 5 at its lower end and with the reamer lugs 6 on its exterior wall immediately above said teeth. Reamer teeth 7 have dove-tailed portions engaging dove-tailed slots 8 in the exterior wall of

the bushing 3 and these teeth 7 are held in place by the upper end of the shoe 4 when the same is screwed home on the bushing 3. A bushing 9 is placed in the bushing 3 and is connected with said bushing by the ribs 10 on bushing 9 engaging grooves 11 in bushing 3 and the ends of the ribs 10 are engaged by an internal shoulder 12 on the shoe 4 so that the shoe 4 holds the bushing 9 in place. This bushing 9 is of smaller diameter than the bore or bushing 3 and is held in spaced relation from the bushing 3 by the ribs 13 on the interior walls of the bushing 3 so that water can pass between the two bushings from the barrel 2. A shoe 14 is threaded to the lower end of the bushing 9 and the toothed lower end of this shoe extends beyond the toothed end of shoe 4 so that the water escaping from between the two shoes will not reach the core of earth cut by the shoe 14 as the same is protected by the extended lower end of the shoe 14. The core barrel 15 is formed in sections with the lower end of the lower section threaded into the shoe 9 and the different sections are connected together by the threaded sleeves 16. A core 17 is threaded and connected by a sleeve to the upper section and this core carries a cage 18 for the ball valve 19 which is held to its seat by the spring 20. It will thus be seen that the core barrel and its attached parts are connected with the driving barrel 2 and its attached parts through the ribs 10 and the grooves 11 so that said core barrel must rotate with the driving valve. The teeth on the shoes 4 and 14 will cut a hole and the reamers 6 and 7 will ream the hole. A core of earth will pass into the core barrel and this core of earth is protected from the water passing through the device by the extended lower end of the shoe 14. The water passing into the barrel 2 will flow through the passage formed by the ribs 14 and the bushings 3 and 9 and will escape through the space between the shoes 4 and 14 so that the parts will be cooled by this water. Shoe 4 not only acts to hold the reamer teeth 7 in position but it also acts to hold the ribs 10 in the grooves 11.

It is thought from the foregoing description that the advantages and novel features of my invention will be readily apparent.

I desire it to be understood that I may make changes in the construction and in the

combination and arrangement of the several parts, provided that such changes fall within the scope of the appended claim.

What I claim is:—

5. A device of the class described comprising an outer barrel, means at the upper end thereof for engaging a drilling tool, a bushing at the lower end having exterior and interior grooves therein, reamer teeth engaging the exterior grooves, an interior bushing having ribs thereon engaging the interior grooves, a shoe threaded to the
10. 15. 20.

outer bushing and having portions for holding the reamer teeth and the ribs in their grooves, cutting teeth at the lower end of said shoe, a second shoe threaded to the lower end of the second bushing and having cutting teeth at its lower end, an interior sleeve connected with the second bushing and a check valve at the upper end of the 20 said sleeve.

In testimony whereof I affix my signature.

LEWIS P. BRANDEL.
